CORTLANDT J. LANGLEY, OF NEW YORK, N. Y., ASSIGNEE TO CHARLES W. BUMSTEAD,
TRUSTEE, OF HIGHLAND PARK, NEW JERSEY

MATCH BOOK

Application filed January 29, 1929. Serial No. 335,977.

My invention relates to improvements in match books. In an application filed simultaneously herewith, Ser. No. 335,975, I have described a match book in which the cover and the enclosed match cards are formed from a single sheet of stock which makes a simple and inexpensive match book having the appearance of the usual commercial article.

As an improvement on the invention described, I have defined a match book in which the folded stock from which the splints and cards are cut has a filler of wood or other prepared material. Because of its stiffness and good burning qualities, many prefer a splint wholly or partly of wood, but in making cards for match books of wood serious difficulties occur because the fastening of the cover to the card is quite apt to split the wooden stock of the card, and furthermore, when an individual splint is torn from a card the base part will seldom split straight, and thus, the card is very apt to be destroyed before the matches are used.

My invention makes a match card in which the splint has all the desirable qualities of the wood or other prepared material without any of the disadvantages, because when folding the stock that is to be cut into splints I insert a filler of wood or other material which can, if desired, be impregnated against coating, and when the splints are cut the filled part of the card is entirely cut off so that the base of the card is simply the fabric of the kind which is folded to make the splint cards, and so the splints are torn off without affecting the card injuriously and the desired qualities of the match are obtained.

The match book will be better understood from the following description.

Reference is to be had to the accompanying drawings forming a part of this specification in which similar reference characters indicate corresponding parts in all the views.

Figure 1 is a broken perspective view of a sheet of stock from which a plurality of match books can be made.

Figure 2 is a perspective view of the

partly folded stock with the inserts in place.

Figure 3 illustrates a further step in the making of the match book.

Figure 4 is an edge view of the stock after the folds have been completed and cut into splints.

Figure 5 is similar to Figure 4, but with the heads applied to the splints.

Figure 6 is an edge view of the partly folded match book.

Figure 7 shows another step in the operation.

Figure 8 is an edge view of the completed book.

Figure 9 is a perspective view of the completed match book.

While a single match book can be made if desired, it is preferable to simultaneously form a series of match books as the stock can be handled better in a large way and the work in manufacture expedited. To this end a strip of stock 10, wide enough in one dimension to form a plurality of match books is used, the stock being in the other dimension of a size to fold into match books, as will presently appear.

The stock has a strip of striking material 11 applied transversely thereof which when the book is completed and folded will appear on the back of the book so as to make it safer when the match is struck and much less likely to damage the other matches.

The stock strip is provided with spaces 12 and 13, as indicated in Figure 1, which merely define parts to which adhesive is applied and upon which are folded the parts 14 and 15, which are also provided with adhesive, the folds being made along the lines 16 and 17, so that the said parts 14 and 12, and 13 and 15 can be fastened together to form cards which will be cut into splints, as presently described. The folds, as stated, are along the lines 16 and 17 which will form free ends or edges of the match cards and splints.

In the folds are placed the inserts 18 which are preferably wood, but can be of other stiffening and inflammable material, and these inserts extend entirely across the stock but are narrower than the parts 12, 100

13, 14 and 15 of the folds, leaving a selvage or base portion 19 between the inserts and the corresponding outer parts of the fold. Thus, when the folds are completed and the 5 inserts in place, the opposed parts of the stock of each fold will be secured and will overlap the inserts, and when the splints 20 are cut from the thus folded stock the splints and the cards will be united only by 10 the selvages or bases 19, and when a splint is torn off, therefore, only the part 19 is torn and the insert part of each splint has been cut.

After the folds have been completed and 15 the inserts made, the stock can be folded along the line 13' to make the two folds diverge in order that they may be easily dipped. The splints 20 are dipped in any usual or preferred way to produce the heads 20 21. The bases or selvages 19 of the folds are fastened together as by staples 22 or other equivalent fastening means and the stock from the edge of one fold is formed into a short tab 23 forming the short end 25 of the cover, while the opposed fold merges into the extension 24 and 25 forming the other parts of the cover. The long part or flap of the cover is folded over the heads as usual and tucked beneath the short tab 30 23.

I have described the manner of making match books sufficiently to make it clear how the stock is prepared and what the real structure of the book is, but the parts can 35 be operated on in other ways without affecting the invention here claimed which is the particular type of book shown, in which the folded stock merges into the cover material and the cards and splints formed with the 40 insert, as specified.

What I claim is:

1. A match book comprising a match card of folded fabric with a wood filler in the fold, the folded fabric being united at the 45 base of the card behind the inner edges of the filler, the fabric of the splints separated to the base of the card, the filler of the splints entirely separated and the unfolded parts forming a cover for said splints.

50 2. A match book of sheet stock with a plurality of folds united at the base with a wood filler enclosed in the folds and with the folds meeting at the base behind the wood filler and diverging at their free parts, 55 said folds being formed into match splints and the unfolded parts being shaped into a cover.

3. A match book of sheet stock with a plurality of folds united at the base and with 60 a wood filler enclosed in the folds, the folds meeting at the base behind the inner edge of the wood filler and diverging at their free parts, said folds being formed into match splints, the outer fabric of one fold extended 65 to form one part of the cover, and the

outer fabric of another fold extended to form the second part of said cover.

4. A match card comprising a body of wooden match splints; a covering of paper-like material for said splint bodies, and a match card base composed wholly of said 70 paper-like material, the match splints and base being united through said covering.

5. A match book, comprising a card composed of wooden match splints, a paper-like 75 covering for said splints and a base wholly of said covering material, the splints and base being attached through said covering, and a cover for the match cards of said paper-like material, said covers being attached to said base.

6. A match book, comprising a card composed of wooden match splints, a paper-like covering for said splints and a base wholly 80 of said covering material, the splints and base being attached through said covering, and cover members for the card, said cover members being of the same material as the base and covering and forming extensions 85 of the said base.

In testimony whereof, I have signed my name to this specification this 25th day of January, 1929.

CORTLANDT J. LANGLEY.
